UNITED STATES PATENT OFFICE.

CHARLES H. BENCSIK, OF CINCINNATI, OHIO.

AUTOMATIC SWITCH MECHANISM.

1,116,973.

Specification of Letters Patent. Patented Nov. 10, 1914.

Application filed August 1, 1914. Serial No. 854,532.

To all whom it may concern:

Be it known that I, CHARLES H. BENCSIK, a citizen of the United States, and a resident of Cincinnati, in the county of Hamilton and State of Ohio, have invented a certain new and useful Improvement in Automatic Switch Mechanism, of which the following is a specification.

This invention relates to switch devices for use in lines of railway that have means for automatically-closing open switches during the passage of approaching engines or trains that would otherwise be in danger of undue shifting from one track to the other resulting in the loss of life and property, and the object of the invention is to provide positive mechanical means, in connection with the track and the switch-throwing mechanism, that are adapted to be raised or elevated above the ordinary level of the track when the switch is open and to be positively lowered or depressed in an automatic manner by means of a device that is carried by the engine or by the first car approaching the open switch thus closing the said open switch before the fore wheels of said approaching engine or train reach the switch.

The details of structure of this safety device will be fully hereinafter described and particularly pointed out in the claims.

In the accompanying sheet of drawings, Figure 1 is a plan view showing my improvement in set position for use in connection with an open switch; Fig. 2, a side elevation showing the improved trigger-mechanism box in vertical section, and with a side elevation of the cam that is carried by the engine to automatically throw the open switch before the engine can reach the latter; Fig. 3, a fragmentary sectional plan projected from the trigger-mechanism seen in Fig. 2, such trigger being in set position ready for the oncoming train and to release the weighted device that is adapted to instantly throw the switch into closed position for the said train to pass safely onward along the track it is intended to take or use.

1 indicates the cross-ties on which are laid the track-rails 2 and the switch-rails 3, the latter being shown in open position.

4 indicates the inclosing-box for the switch-operating mechanism that is mounted on extended cross-ties alongside the track adjacent the switch-point. Box 4 has a vertical partition 5, on one side of which a

lever 6 is pivotally-mounted at 7, a weight 8 being adjustably and removably mounted on said lever and the latter having a handle-formed upper or outer end 9 for use in manually-operating the switch when required. The lower end of the lever 6 has a pendent angular-extension 10 whose lower end, in turn, is pivotally-connected with a rod 11 that leads through the end wall of 60 the box 4 to the bell-crank lever or arm 12 that is pivotally-mounted on an extended cross-tie and is pivotally-coupled to the outer end of the switch-bar 13.

14 is a trigger-arm pivotally-mounted on 70 a pin 15 that is supported in a pair of spaced projections 16 on the face of partition 5 opposite to that on which the weighted-lever 6 is mounted. One end of the trigger-arm 14 is forked so as to receive 75 a horizontal latch-bolt 17 that is pivotally-connected in place near its outer end by means of a transverse pin 18 that crosses an enlarged or flattened portion of the bolt. The other end of the trigger-arm is inclined 80 at 19 and thereby adapted for frictional, actuating engagement with an emergency lock-lever 20 that is pivotally-mounted at 85 21 on a stud 22 extending from the same face of partition 5 as that of the projections 16, but below the latter, as best seen in Fig. 2. The lower end of the lock-lever 20 is forked to receive the inner end of a long rod 23 that extends quite a distance alongside and parallel to the track and has a terminal 24 that slides in a vertically-slotted bearing 25 mounted on a tie-extension remote from the switch. A spiral spring 26 is carried by the outer end of the rod 23 between the said bearing 25 and a collar 27, 95 the latter being adapted to be set on the rod to suit the desired tension or resilient adjustment thereof in the operation of the switch-throwing device.

28 indicates a transverse shaft mounted in 100 a pair of upright bearings 29 on said remote tie-extension that is convenient to the outer end of the rod 23, the latter being pivotally-connected to a crank-arm 30 that extends from the shaft 28 adjacent the outer 105 one of the bearings 29.

31 indicates a convex-faced arm or cam extending laterally from the shaft 28 adjacent the inner one of the bearings 29, and 32 is a shoe or cam adapted to be attached to 110 the fore end of the engine, ahead of any of the track wheels thereof, and positioned

so that it lies vertically outside of the rails of the track, the distance depending on that of the cam or arm 31 from the rails. Shoes 32 are mounted at both sides of the engine, 5 preferably between the rear of the pilot and the foremost wheels thereof, and their lower cam-faces slope in opposite directions so that the spring-controlled rod 23 and the trigger devices can recover and become at 10 rest without shock after the fore face of the cam or shoe 32 has engaged the cam 31 and thrown the lock-lever 20 into frictional-engagement with the inclined face 19 of the trigger-arm 14 that rocks or swings the latter and causes the withdrawal of the latch-bolt 17 from engagement with the weighted-lever 6 that now instantly drops to forcibly 15 actuate the connecting-rod 11, bell-crank lever 12 and switch-bar 13 for closing the switch-rails 3 before said foremost wheels of the engine can possibly take the wrong course into the switch and assuring the safe and direct onward passage of the train along the track-rails 2.

25 When the shoe or cam 32 on the engine has depressed the cam 31 on the shaft 28 the spring 26 is compressed and, as soon as the fore-face of the shoe 32 has passed said cam 31, the outer end of the lock-lever 20 becomes in locking-engagement with a notch or shoulder 33 on the trigger-arm at the inner end of its inclined face 19.

30 The switch can now be operated by means of the handled-lever 6 for its intended use while the bolt 17 is thus held in retracted position by the engagement of lock-lever 20 with the notch 33 in the trigger-arm, and, as it is intended that the said handled 35 weighted-lever 6, when elevated, shall not advance beyond the inclination shown in Fig. 2 that is away from a perpendicular position, said lever 6 should be locked in its elevated position while the switch is being used, the locking being effected by means of 40 the latch-bolt 17 whose outer end has a convenient handle 34 whereby the bolt can be readily drawn outwardly sufficient to permit the release of the lock-lever 20 from said 45 notch 33 which is now automatically done by the expansion of the spring 26 that causes the rod 23 to move lengthwise or longitudinally forward and the lock-lever 20 to be swung backward along the inclined face 19 of the trigger-arm until the normal 50 relation seen in Fig. 3 is attained, the latch-bolt 17 in the meantime being projected forwardly by the switchman so that its inner end shall lie in the downward path of the 55 weighted-lever 6 and hold it in the elevated position seen in Fig. 2.

60 Should the switchman fail or neglect to pull the latch-bolt 17 outwardly to release the weighted-lever 6 after a switching operation and thereby close the switch in ordinary use, the device then remains in the

set position seen in the drawings, and especially in Fig. 2, ready for emergency use when the moving train approaches and automatically closes the switch-rails in the manner referred to above in describing the 70 details of the device.

75 It will be observed that this device can be readily applied without any alteration or change in the track or switch in general use whatever, and that the actuating block or cam carried by the engine is extremely simple, readily secured in place for action and not easily gotten out of order or apt to interfere with the working of the engine in the least or at any time.

80 The boxing 4 around the trigger mechanism shields it from the elements, ice, snow, dust, cinders and other possible deleterious and damaging effects, and the weight on the lever 6 can be readily removed or adjusted 85 when necessary as it is mounted outside said casing or boxing.

I claim:—

1. A safety railway-switch closing device comprising a switch-bar, a bell-crank, a rod, 90 a pivotal weighted-lever, a latch-bolt, a pivotal trigger-arm adapted to carry said latch-bolt into and from detaining-engagement with said weighted-lever, a swinging lock-lever one end of which is adapted to frictionally-engage said trigger-arm, a longitudinal rod pivotally-connected at one end to the other end of said lock-lever and carrying a coil-spring at its other or remote end, a transverse shaft mounted on a lateral 100 cross-tie extension at said remote end of said rod, a crank-arm on said shaft pivotally-connected to said remote end of the rod, a cam mounted on said shaft near the track-rail, and a pendent member on the engine 105 projecting outside the line of the track-rail and adapted to engage the said cam or lateral arm as the engine advances toward an open switch to automatically throw or close said switch before the engine can reach it 110 and thereby direct the train onward in its proper course along the track.

2. A safety railway-switch closing device comprising a switch-bar, a bell-crank, a connecting-rod, a pivotal weighted-lever connected to said rod, a horizontal latch-bolt, a pivotal trigger-arm having one end thereof pivotally-connected to said bolt and adapted to carry it into and from detaining engagement with said weighted-lever when 115 the latter is in elevated position and having its other end notched and inclined, a swinging lock-lever having one end thereof adapted to frictionally-engage said notched and inclined end of the trigger-arm, an in- 120 closed supporting-frame, a longitudinal rod extending remotely along the outside of the track and pivotally-connected at its inner end of an extension on said lock-lever, a coil-spring on the longitudinal rod, a trans- 125

verse shaft mounted on a lateral cross-tie extension at the outer or remote end of said longitudinal rod, a crank-arm on said shaft pivotally-connected to the remote end of the longitudinal rod, a cam or lateral arm mounted on the shaft near its inner end adjacent the track-rail, and a pendent shoe or cam member on the engine adapted to engage the cam on said shaft whereby the trigger devices are actuated automatically to release the latch-bolt and the weighted-lever,

the latter in dropping causing the open switch to close before the fore-wheels of the engine or advancing train can enter the switch but to maintain them in the proper 15 onward course on the track intended to be used.

CHARLES H. BENCSIK.
